APPARATUS FOR ACCELERATING CHARGED PARTICLES BY CAUSING THEM TO PASS THROUGH PERIODICALLY REVERSING POTENTIAL FIELDS

Rolf Wideroe, Oslo, Norway, assignor to Aktiengesellschaft Brown, Boveri & Cie, Baden, Switzerland, a joint-stock company

Application August 6, 1947, Serial No. 766,698
In Norway January 31, 1946Section 1, Public Law 690, August 8, 1946
Patent expires January 31, 1966

7 Claims. (Cl. 250—27)

1

This invention relates to apparatus for accelerating charged particles such as electrons, ions, and the like to high velocities, and in particular to the type of apparatus in which acceleration of the particles is attained by causing them to pass through consecutively arranged fields, the directions of which are alternately reversed so that the particles repeatedly encounter an acceleration field. The fields are usually electrostatic and are established by seriatim arranged tubes charged from a high frequency source and through which the particles are passed. Adjacent tubes in the series are connected to opposite terminals of the source so as to be charged to opposite polarities and the particles are accelerated in steps as they progress through the fields.

In Fig. 1 which illustrates the already known principles involved, the fields are established electrostatically by a row of tubes T, T₁, T₂, T₃, T₄ . . . etc. Alternate tubes in this row, i. e. T₁, T₃, T₅ . . . , and T₂, T₄ . . . are connected to the same terminal of an alternating current source and preferably one having a high frequency characteristic, the odd numbered tubes T₁ etc. being connected to terminal P and the even numbered tubes T₂ etc. connected to terminal P'. If an electron for example is inside of tube T₁ which happens to be charged negative at the instant assumed, it will not only find a free path ahead of it but will also be accelerated in the direction of the next adjacent positively charged tube T₂ and drawn into the latter. After entering the tube T₂, the polarity of the field in tube T₂ changes to negative and the polarity of the following tube T₃ becomes positive during the time interval when the electron traverses the tube T₂ and consequently a further acceleration of the electron is obtained. This step-by-step method of increasing the velocity of the particles continues throughout the whole row of tubes. As the frequency at which the fields of the tube are reversed is maintained constant, and the passage of the particles from one tube to another must be properly timed with the change in polarity of the tube fields, it will be evident that because of the continually increasing speed of the particles, successive tubes in the row must be of increasing length.

If very high terminal velocities of the particles is desired and high frequencies are used for reversing the accelerating fields, it will be obvious that extremely long tubes will be required. The long tubes not only present space problems but

2

also obviously require a high charging current which of course necessitates correspondingly large high frequency generator apparatus. These drawbacks limit the practical range of operation of the apparatus to voltages of a few million volts which hereinafter is shortened to MV, and restricts its use to the more heavier of the ions.

The object of the present invention is to provide an improved construction for charged particle accelerators of the type described which overcomes the disadvantages inherent in the prior known structures, the objective being attained by an apparatus for the acceleration of charged particles such as electrons, ions, etc., comprising an evacuated chamber, an electrode system of spaced tubes and a source of high frequency alternating current for energizing the electrodes of said system to establish potential fields of alternate polarity in the spacings between said tubes, said particles passing through said potential fields and being accelerated in accordance with periodic reversals of said fields, and the improvement wherein said electrodes constitute a part of a high frequency transmission line of the coaxial cable or Lecherwires type and have a spacing corresponding to a fourth part, or a multiple thereof, of the wave length of the standing voltage waves in said transmission line, said electrodes being so arranged that as to each electrode the particles move therein between points that at the same time possess different potentials.

Fig. 2 illustrates one embodiment of an accelerating device constructed in accordance with the invention. The two high frequency conductors establishing the transmission line are formed by the hollow cylinders a₁, b₂, a₃, b₄, and the rods b₁, a₂, b₃, a₄, and the charge particles travel through the potential fields at I, II, III and IV in succession. The frequency of the standing voltage waves is selected so that the electrons or ions pass between the ends of successive hollow cylinders in exactly one-half cycle (or a multiple of the same) of the high frequency current. The potential between the conductors will therefore be equal (for example as shown in Fig. 2 where the full drawn line b₁b₂b₃b₄ indicates the potential of the one conductor and the dotted line a₁a₂a₃a₄ indicates the potential of the other conductor) each time the charged particles pass through a potential field, and they are therefore accelerated each time with the entire high frequency current.

Since the velocity of the particles increases with increasing particle voltage, the cylinders

are made successively longer in accordance with the following mathematical relationship

$$v = c \frac{\sqrt{U^2 + 2U\epsilon}}{U + \epsilon} \quad (1)$$

where

$$\epsilon = \frac{m_0 c^2}{e}$$

c =speed of light

v =speed of the particle

m_0 =inertia of the particles at rest

e =charge of the particle

U =kinetic energy of the particles measured in units of electron-voltage.

The wave lengths of the standing waves of the transmission line shall consequently be made longer.

In order for the aforesaid condition of resonance to be met and at the same time the electrons accelerated with the maximum alternating current, the wave length $\lambda \sim$ and the length of the standing waves λ_{st} should meet the requirement

$$\frac{p}{2} \lambda_{st} = \frac{v}{c} q \lambda \sim = l \quad (2)$$

where l =distance between the electrodes, (p) and (q) are whole numbers that indicate the number of standing waves

$$\left(\frac{p}{2}\right)$$

there are between the electrodes, and how often (q) the applied high frequency alternating current changes between the passage of the particles through the length of a tube.

Since λ_{st} will always be smaller than $\lambda \sim$, (p) and (q) are selected so that the best values for $\lambda \sim$ and l are obtained. If, for example, electrons whose speed is about equal of the speed of light are to be accelerated, it will be best to choose $(p)=3$, and $(q)=1$, and then the following is obtained:

$$\lambda_{st} = \frac{2}{3} \lambda \sim = \frac{2}{3} l \quad (3)$$

When the speed of the particles is smaller than half the speed of light, $(p)=(q)=1$ can be selected and the following is obtained:

$$\lambda_{st} = 2 \cdot \frac{v}{c} \lambda \sim = 2l \quad (4)$$

This latter corresponds to the apparatus illustrated in Fig. 2.

The wave length for the standing waves can be adjusted as shown in Fig. 2a by the insertion of materials between the conductors, these materials having a dielectric constant, or permeability, greater than one. In order to obtain especially short wave lengths, it is preferable to insert material 75 with high dielectric constant in the neighborhood of the points of voltage maxima (voltage anti-nodes) while material 76 with high permeability should be placed preferably in the neighborhood of the points of zero voltage (voltage nodes). These materials should likewise have small alternating current loss characteristics. This latter should also be true for the transmission line itself. The wave lengths of the standing waves can also be adjusted with the aid of inductances 61 and capacitances 62 connected in series and parallel, respectively as shown in Fig. 2. To prevent absorption losses by the charged particles due to collision with the

gas molecules, their acceleration should preferably take place in a high vacuum, which may be accomplished by enclosing the tubes in a container (as shown in Fig. 5 and 6) and evacuating the same.

The apparatus illustrated in Fig. 2 is especially suitable for the acceleration of relatively slow particles such as for example, ions below 10 MV, since with great speeds of the particles, long cylinders and very high frequencies are then necessary.

Fig. 3 illustrates an embodiment of the invention which is particularly suitable for the acceleration of very rapid particles with about the speed of light. This drawing also shows in the same way as Fig. 2 transmission line systems of Lecherwires consisting of alternating short hollow cylinders (a) and rods (b) in succession. In this case, the acceleration cylinders are made sufficiently short that the amplitude of the applied high frequency voltage changes but only a little in the time required for the electrons to move through the cylinders. If, for example, the cylinder is made 40 cm. long and $\lambda \sim = 6$ m. is chosen, five acceleration tubes can be used in which the electrons are passed during the time that the amplitude of the high frequency voltage changes by no more than

$$\cos \pm 30^\circ = 86.7\%$$

After the electrons have travelled through the first five tubes, they can then be further accelerated in another set of five tubes by another high frequency voltage wave displaced 60° in phase from the wave associated with the first five tubes; and then still further accelerated in a third set of five tubes to which is applied a third voltage wave displaced 60° in phase from the wave associated with the second set of tubes. In this manner, the electrons can be accelerated in an uninterrupted series with the aid of a three-phase high frequency voltage supply source, the phases being designated on the drawing by U_R , U_S and U_T .

In order to attain the highest possible voltage on the particles for a given overall length of the accelerating tube system, the accelerating tubes are to be made short. If the frequency of the applied alternating voltage is not to be too high, the relation

$$\frac{\lambda \sim}{\lambda_{st}}$$

is to be made high, i. e. materials with very high dielectric constant and permeability are to be used. The relation

$$\frac{\lambda \sim}{\lambda_{st}}$$

can be brought up to above 15 ($\epsilon_u > 225$) and possible even up to about 35-40. It should be possible therefore to make the acceleration tubes about 10 cm. long, and to attain an acceleration of from 1 to 2 MV per meter.

If the speed of the particles is much lower than the speed of light, the apparatus illustrated in Fig. 3 can be used, but with the same values for the two wave lengths, a correspondingly smaller number of cylinders per phase must be used. If $v=0.2c$, only one acceleration tube per phase is obtained. If the speed of the charged particles is lower still, the acceleration voltage diminishes. If $v=0.133c$, then with one acceleration tube per phase, and a two-phase system, an acceleration voltage that amounts to $\cos \pm 45^\circ$ (70% of the maximum alternating voltage) is obtained.

From this, it is seen that the range of use of the apparatus shown in Fig. 3 adjoins the range where it becomes advisable to use the apparatus illustrated in Fig. 2.

If it is desired to avoid apparatus of unduly great length (100 MV deuterons would require an overall length of apparatus of from 110 to 120 meters, with an initial acceleration voltage of 200 kv. and a wave frequency of 50 mega-cycles, $\lambda \sim 6$ m.), and

$$\left(\frac{\lambda}{\lambda_{st}}=15\right)$$

the particles can be given a circular motion by magnetic control fields and thereby made to pass through one or more acceleration tubes over and over again until the desired high final velocity and voltage is attained for the particles. Since the number of revolutions of the particles can be made very great, the initial acceleration voltage can be made much lower, for example about 10 kv., than that required for the straight-line tube arrangements of Figs. 2 and 3.

Fig. 4 illustrates, in somewhat diagrammatic form, an accelerating device for charged particles embodying the principles of the invention and wherein the particles are accelerated along a circular path. The device functions in accordance with the principles shown in Fig. 2 and is comprised of two symmetrically arranged transmission lines of concentric form. One line consists of an outer conductor 6 and an inner conductor 2 connected with the feed lines 5 and 1 respectively; the other line consists of an outer conductor 7 and an inner conductor 3 connected with the feed lines 5 and 4, respectively. Since the speed of the particles will be greater than .5 c., as previously stated, λ_{st} can be selected equal to $\frac{2}{3}$ of the circumference $2\pi R$. Two voltage nodes are then obtained, these being at 10 and 10a, where the electrodes can be short-circuited. The ends 11 and 12 have voltages displaced in phase by 180°, and at these places are located the high frequency voltage convexities. The hollow cylinder 8 between points 10 and 10a past 16 is at earth potential and the cylinder is cut apart at point 16 in order to prevent eddy currents from being set up by the magnetic field 15. The two energy electrodes could moreover be disconnected at the nodes 10 and 10a, and the whole intermediate section of the acceleration tube (that can be isolated from the energy conducting electrodes) placed at ground potential.

In Fig. 4, two energy conducting electrode units are utilized and these are displaced 180° in phase. In lieu of the illustrated construction, the two electrode units could be replaced with a single electrode unit, in which $\frac{1}{4}$ of the wave length of the standing wave forms a part of the acceleration tube while the other portion of the acceleration tube from the node of the wave to the potential field can be grounded and isolated electrically from the high frequency alternating voltage.

Such an arrangement is illustrated in Fig. 5 where there is a vacuum vessel 23, 24 with a lateral projection 26 for the electron gun 25, as well as an acceleration system. The transmission line consists of a single electrode unit comprising two tubes 19 and 20 which at the point 18 (where a voltage node would form) are joined together, whilst the other end of the transmission line is connected to the high-frequency generator 21. At the point 17 where the particles

are accelerated there is a high potential between the electrodes; there is a voltage antinode here. Along the path 18 to 17 (over 27) the circular orbit 28 of the particles lies within an earthed tube 22, and the particles which are brought through the opening 27 into the acceleration path cannot be influenced here by the acceleration voltage.

The acceleration frequency has thus to be made equal to the frequency of circulation of the particles, or equal to a multiple of this frequency, so that the particles are accelerated during each revolution by the potential field existing at the point of entrance 17 to tube 20. The magnetic control field, which compels the particles to follow a circular path, flows perpendicular to the plane of the drawing, Fig. 5, in the form of an annulus, the inner and outer boundaries of which are defined by the inner and outer diameters of the control field poles 29, 30 shown in Fig. 6. To simplify illustration, the boundaries only of this control field are shown in Fig. 5 and are designated by the broken lines 15'. The circular tube 22, 19 is interrupted at the entrance 17 in order that the magnetic field should not cause any short-circuit currents.

In Fig. 4, the electrodes 2 and 3 within which the electrons are accelerated are shown connected through transformer 13 to a source 14 of high frequency current. Electrodes 2 and 3 together form a toroidal tube that is open between the electrodes 11 and 12, the tube being split lengthwise or formed by parallel insulated conductors. In order to nullify centrifugal forces, the magnetic field 15 previously referred to, is set up in a plane perpendicular to the plane of the drawing, and the Lorenz forces produced thereby serve to guide the accelerating electrons along a circular path within the electrode tube. The circling electrons may be stabilized in both radial and axial directions by reducing the strength of the magnetic field in a radially outward direction, but at a rate less than proportional to R^{-1} .

If the voltage of the electrons increases, their mass will likewise increase and the magnetic field must therefore increase in order to annul the increased centrifugal force. The field 15 can therefore be produced from an alternating current source at a comparatively low frequency, for example 50 cycles, in order to control the path of the electrons. In order that the electrons shall always follow approximately the same circular path of radius R, the relation between the control field 15, which can be designated B, and the electron voltage U should be as follows:

$$B = \frac{1}{cR} \sqrt{U^2 + 2U\epsilon} \sim \frac{U}{cR} \quad (\text{when } U \gg \epsilon) \quad (5)$$

From Equation 5, it can be seen that the control field B is accordingly to increase substantially proportional to the electron voltage. This equation further indicates that the high frequency electron accelerating voltage applied to the electrons must during the course of the electron acceleration change in proportion to

$$\frac{dB}{dt}$$

i. e. the voltage is to diminish proportional to $\cos \omega t$, when the control field B increases proportional to $\sin \omega t$. If at the beginning of the electron acceleration, the accelerating voltage is made somewhat too high, the above change can be omitted and a constant high frequency voltage

employed. If the magnetic field B increases more slowly than proportional to time, the electrons, due to the constant acceleration voltage, will receive too high a voltage and the radius of the electron path will increase. Since the speed increases less than does the circumference of the circle, the electrons will reach the electrodes too late. This phase lag will increase with each revolution of the electrons and cause the electron voltage to diminish. Such action will continue until the electron path is balanced exactly at the correct acceleration voltage, that corresponds to

$$\frac{dB}{dt}$$

In this manner, a stable equilibrium state for the radius of the electron path is obtained.

When the electrons enter the accelerator with an initial voltage of 460 kv., for example, they have about 85% of the speed of light. The speed will increase subsequently to the speed of light (at 10 MV, the difference is only about 0.23%). In order that the time of revolution shall be one high frequency period in all cases, the radii of the electron paths, or else the frequency must be changed during the acceleration period. If the former is selected, the control field B and the acceleration tube must be enlarged in the radial direction sufficiently to permit the necessary enlargement of the electron paths, (for example from 0.85 to 1). In view of the fact that it is advantageous from a constructional point of view to have as narrow a magnetic control field as possible, the initial voltage of the electrons should be as high as possible. It is therefore of advantage constructionally to arrange the electron gun by which the electrons are produced outside of the acceleration tube as shown in Fig. 5. With such construction, the electrons can then be introduced with somewhat too great a voltage, so that they must pass along the inner wall of the acceleration tube. A few short and thin retarding foils 40 applied there will slow down the entering electrons so that the latter receive exactly the voltage that corresponds to the innermost electron path. With increasing voltage, the radius of the path increases and the electrons are no longer disturbed by the retarding foils. Since the electrons can be introduced only during a short portion of a period of the high frequency field applied to the accelerating electrodes, the electrons are to be accelerated even in the electron gun with high frequency fields of the acceleration frequency, and are emitted only during a certain part of the period. The electrons can be introduced preferably at parts of the orbit corresponding to the nodes of the acceleration voltage, i. e. where the energy conductor is not present.

The rotating electron charge limited in the azimuth sense will induce a weak alternating current when it passes through a condenser 41 that is placed in the vacuum tube at places where the acceleration tubes are on earth potential. This alternating voltage can be amplified in an amplifier 42 and used for the control of the high frequency generator 21 in known manner as described for example in "Radio Engineer's Handbook" by Terman published 1942, at pages 510-516. This is especially important when it is desired to change the frequency of the generator during the acceleration period, in order to meet the condition of resonance. In the latter case, the constants of the transmission line are to be likewise changed so that the generator will work

in resonance. This can be accomplished for example by using an inductive winding 44 connected between the leads from generator 21 and which is wound upon one leg of a rectangular iron core 45. Wound upon another leg of the core is a premagnetizing winding 46 energized from a source of direct current 47 through a potentiometer 48 by which the permeability of the core 45 can be adjusted.

For controlling potentiometer 48 automatically, use can be made of a discriminator which supplies a control voltage according to the variation in frequency of generator 21, the control voltage in turn being applied to a servomotor 57 which then adjusts the setting of the potentiometer in one direction or the other dependent upon the sense of the frequency variation. A suitable discriminator circuit for this purpose can be found described on pages 654ff of the above mentioned handbook.

The tubes forming the circular path in Fig. 5 can also be slotted longitudinally at a plurality of places around the tubes as shown by slots 56, if desired.

An important constructional advantage is obtained if the magnetic control field B is closed through the surfaces inside the paths of the electrons and to apply the magnetizing winding around the iron core formed thereby as shown in Fig. 6. The result of this however will be that the varying core field will produce an electrical swirling field that tends to slow down the movement of the electrons. Since the core field will fill up only a part of the circular surface, for example one-half of it, the induced opposed voltage will be for example only one-fourth of the increase in voltage that corresponds to the increase in control field. The accelerator voltage in this case is to be made to agree, i. e. 25% greater than without the swirling field.

Fig. 6 shows a section through the central axis 34-34 of an accelerating device of the kind illustrated in Fig. 5. The vacuum vessel is indicated by the reference numerals 23, 24, whilst 22 is the earthed tube extending from 18 through 27 to point 17, and the 19 and 20 are the two electrodes of the transmission line. The flux of the magnetic field for guiding the particles is indicated by the dotted line 32, whilst 31 is the iron core. The magnet poles of the magnetic guide field are indicated by 29, 30 and 33 is the winding for exciting the magnetic field, the winding 33 being energized from a source of alternating current 33'.

When the electrons have attained the desired voltage, they can be withdrawn from the acceleration chamber by suddenly switching in an additional magnetic field (positive or negative) that is superposed upon the control field. This can be effected through the instrumentality of a transformer 49, the secondary 49a of which is connected in the energizing circuit of winding 33 and the primary 49b of which is energized at the proper instant from a voltage source 59. In the same manner as in the case of a betatron tube, the electrons can be made to hit a target for the production of X-rays, or are else removed from the tube with the aid of deflecting electrodes provided for such purpose.

In order to attain a more satisfactory introduction of the electrons into the accelerator, an additional magnetic field can be employed, the latter being switched in suddenly at the proper instant to bring the electrons away from the retarding foils mentioned previously, or from other

constructional elements in the vacuum chamber that might hinder their circulation.

Finally it should be mentioned, by way of example, that with a radius of the electron path of 1.5 meters, and a maximum control field induction of about 11,000 gauss, a maximum kinetic energy of about 500 MV for the electrons can be attained. The acceleration frequency should be about 32 mega-cycles (wave length $\lambda \sim 9.4$ meters), whereby a frequency of about 50 cycles for the control field (acceleration time-max. $\frac{1}{200}$ sec.) would make possible an acceleration voltage of about 10 kv. maximum.

If it is desired to accelerate ions according to the principle employed in the Fig. 4 or 5 construction, the speed interval for the particles will be so great that the resonance condition can not be met with a constant acceleration frequency by changing the radii of the path. Great difficulties will also be met with in changing the acceleration frequency and the constants of the energy conductor within the required range. In this case, where

$$\frac{v}{c}$$

in Equation 2 is small, a corresponding great value for q can be selected and thus the revolution frequency of the ions synchronized with a fraction of the acceleration frequency. If the speed of the ions increases, as mentioned earlier, the radius of the path will increase and the ions will automatically meet the resonance condition and hold fast to this below-synchronism movement. If the magnetic control field diminishes according to the equation

$$B = B_0 \left(\frac{R}{R_0} \right)^{-K} \quad (6)$$

where $0 < K < 1$, the voltage of the ions U and B and B_0 is the magnetic induction for the radii B , respectively B_0 , path radius R , speed v and the revolution frequency v are determined by the following Equations 7 to 10, that hold true for the non-relativistic range ($U \ll \epsilon$). ($B_{0,t}$ is the induction at the time t):

$$U = \frac{c^2 B_{0,t}^2 R_0^{2K}}{2\epsilon} R^{2(1-K)} \quad (7)$$

$$R = \left(\frac{2U\epsilon}{c^2 B_{0,t}^2 R_0^{2K}} \right)^{\frac{1}{2}(1-K)} \quad (8)$$

$$v = \frac{c^2 B_{0,t} R_0^K R^{(1-K)}}{\epsilon} \quad (9)$$

$$v = \frac{c^2 B_{0,t} R_0^K R^{-K}}{2\pi\epsilon} \quad (10)$$

For protons $\epsilon = 930$ MV and for deuterons 1860 MV. When the revolution frequency v is to be constantly equal to the following:

$$v_0 = \frac{c^2 B_0}{2\pi\epsilon} \quad (11)$$

this gives the following equations between the magnetic field $B_{0,t}$ (that varies only with time) and the path radius R and the voltage U respectively:

$$R = R_0 \left(\frac{B_{0,t}}{B_0} \right)^{1/K} \quad (12)$$

$$U = \frac{c^2 B_0^2 R_0^2}{2\epsilon} \left(\frac{B_{0,t}}{B_0} \right)^{2/K} \quad (13)$$

With the aid of Equation 13, when

$$B_{0,t} = B_0 + \frac{dB}{dt} \cdot \Delta t$$

it is easy to calculate the acceleration voltage necessary for synchronism to be as follows:

$$u = \frac{2\pi R_0^2}{K} \frac{dB}{dt} \quad (14)$$

When the path radius, as a result of increase in voltage, approaches the greatest value that is possible constructively, the ions are to be brought out of synchronism by means that will be described later. With asynchronous movement, the ions in the middle are not accelerated and, as a result of the increase in the control field, the path radius therefore will diminish. This continues until the ions, whose speed of circulation constantly increases, attain a higher sub-synchronous frequency ($q_2 < q_1$) and synchronize with a new fraction of the acceleration voltage frequency, so that they can be accelerated again.

In this way, the operation is continued until the ions have attained their maximum voltage. The acceleration frequency is to be selected so high that a relative difference between the last two sub-synchronous frequencies

$$25 \quad \left(\text{i. e. } \frac{q_2 - 1 - q_1}{q_1} \right)$$

is smaller than the difference between the greatest and smallest path radius. If deuterons with 100 MV are to be accelerated, the maximum speed will be about 0.315 c. If the magnetic control field maximum is about 11,000 gauss, the greatest path radius will be about 1.9 m. The smallest multiple of $q=5$ is selected to agree with an acceleration frequency of 39.5 m. cycles or $\lambda \sim 7.6$ m. If λ is made to equal $\lambda \sim$ (i. e. $\epsilon\mu=1$), the spacing between two voltage maxima ($p=3$) will be 11.4 m. and the maximum voltage will hereby lie almost exactly at the acceleration electrodes of the acceleration tube. The smallest path radius will be 20% smaller than the greatest, i. e. about 1.58 m. When the frequency of the control field is 50 cycles and $K=\frac{2}{3}$, the maximum synchronous voltage will be $u=11.8$ kv.

In order to bring the ions out of synchronism, when the "frequency change" is to occur, various methods can be used. The acceleration frequency could be changed somewhat, in the known way, at definite times. It is also possible to change the acceleration voltage in the known way and to permit its value to descend below the previously calculated "synchronous value" (Equation 14). The modulating frequency introduced into generator 21 by the modulator 43 would in this case need to diminish about according to an e^{-t} function and the synchronous and asynchronous time intervals (that will be approximately equal in size) would have to be adjusted so that the path radii would not exceed the permissible limits. Synchronism could also be annulled by increasing the necessary synchronous voltage u above the acceleration voltage present, that is assumed as being varied proportional to

$$\frac{dB}{dt}$$

i. e. proportional to $\cos \omega t$. This can be accomplished for instance by changing the control field through use of a modulator 51 connected in the circuit of energizing winding 33, the modulator being supplied from a relatively low frequency alternating current source 52, and thus periodically increasing

$$\frac{dB}{dt}$$

11

but without changing the acceleration voltage to agree. A simpler solution would be to change the form of the poles of the control field so that the control field diminishes less greatly (i. e. K becomes smaller) when the greatest path radius is reached. One suitable arrangement is illustrated in Fig. 6 where it will be noted that the outer edges of the upper and lower confronting pole faces 29, 30 terminate in annular protuberances 53. By reducing K from $\frac{2}{3}$ to $\frac{1}{3}$ for instance, the synchronous voltage will rise to the double value, this being sufficient to eliminate synchronism. The same thing could likewise be attained by giving the acceleration electrodes a form such that the direction of the potential field changes and the longitudinal field component becomes smaller with the greatest path radius. In this way the acceleration voltage can be made smaller and can be brought below the synchronous value, so that synchronism is eliminated. In order that these "geometrically conditioned" solutions can be employed (which could likewise be used simultaneously) the acceleration voltage normally must not exceed the synchronous voltage more than 30% for instance and therefore must be varied proportional to

$$\frac{dB}{dt}$$

as mentioned earlier.

The methods mentioned here could of course be used likewise for the acceleration of electrons when the original speed is so small, that the increase in speed exceeds the expanse of the control field in radial direction.

In conclusion, a "gigator" according to this invention for 100 MV deuterons with a greatest path radius of about 1.9 m. will weigh less than 130 tons and would therefore be much cheaper to construct than a corresponding cyclotron with a weight of over 5000 tons. It has likewise been shown that the gigator can accelerate ions likewise to considerably higher voltages than the apparatuses disclosed heretofore.

I claim:

1. In an apparatus for accelerating charged particles, a two-wire transmission line comprising a series of inner tubular electrodes arranged in spaced end-to-end relation and a conductor individual to each electrode, each said conductor extending longitudinally of and spaced outwardly from the electrode associated therewith, one end of each said conductor being connected with the adjacent end of the electrode preceding the electrode with which that conductor is associated and the other end of each said conductor being connected with the adjacent end of the electrode following the electrode with which that conductor is associated, and means for connecting said series of tubes and conductors to a source of high frequency alternating current to establish potential fields of alternate polarity in the spacings between the ends of adjacent tubes effective to accelerate said charged particles introduced into said series of electrodes at one end thereof, the spacing between electrodes in the electrode series corresponding to a fourth part, or a multiple

12

thereof of the wave length of the standing voltage waves produced in said transmission line.

2. Apparatus for accelerating charged particles as defined in claim 1 and which further includes capacitances arranged in parallel in said line between said conductors and electrodes and inductances arranged in series with said conductors.

3. Apparatus for accelerating charged particles as defined in claim 1 and which further includes dielectric material disposed at voltage anti-nodes in said line and high permeability material disposed at voltage nodes in said line.

4. Apparatus for accelerating charged particles as defined in claim 1 wherein said series of tubular electrodes are arranged rectilinearly.

5. Apparatus for accelerating charged particles as defined in claim 1 wherein the spacing between potential fields equals approximately half the length of the standing voltage waves in said transmission line, and wherein the wavelength of the high frequency alternating current is relatively much greater than that of the standing voltage waves whereby the amplitude of the voltage wave changes only slightly during the time required for the particles to pass between two or more potential fields.

6. Apparatus for accelerating charged particles as defined in claim 5 wherein said potential fields are established in groups of at least two and said groups of fields are energized respectively by separate phases of a symmetrical source of high frequency alternating current.

7. Apparatus for accelerating charged particles as defined in claim 1 and wherein a source of alternating current having the same frequency as that which establishes said potential fields is utilized for injecting said charged particles into said electrodes.
